STRAP DISPENSER

John W. Culpepper, 3 La Fayette Drive, Jericho Vt., and Edward J. Stahnke and Alvin L. Winkler, Chicago, Ill.; said Stahnke and said Winkler assignors to Acme Steel Company, Chicago, Ill., a corporation of Illinois

Filed May 7, 1963, Ser. No. 278,658

10 Claims. (Cl. 242—78.6)

The present invention relates to the dispensing arts, and more particularly to a new and improved machine and mechanism for dispensing strapping and like materials from coils thereof.

It has been common practice in the past to mount or support a coil of strapping material on a rotatable frame or reel and to rotate the reel, either manually or by power, in order to turn the coil and thereby feed the material therefrom. The prior utilization of this simple practice with unsophisticated mechanisms has been adequate for many purposes, but certain problems, not heretofore entirely satisfactorily or inexpensively solved, have often been encountered, particularly where the coils of material being dispensed are relatively heavy, the desired feeding of the material is intermittent or at varying rates, and where the material being dispensed is resilient and therefore difficult to command and control. In the dispensing of metal strapping, for example, all of these conditions are usually present. The coils of metal strapping are relatively heavy and their rotation cannot ordinarily be stopped instantly when the need for additional strapping ceases. Neither is it easy instantly to change the rate of rotation of the metal coil in response to a reduction in the rate at which the strapping is used. As a result, over-run of the coil is often encountered and a slack or un tensioned length of strapping is released from the coil. This has heretofore been particularly troublesome in the dispensing of steel strapping and the like, for the strapping is often quite resilient and is usually wound in coils having a radius of curvature substantially less than that of the so-called "coil-set" or "bundle curve" (residual curvature), if any, of the strapping. As a result, un tensioned or slack lengths of such metal strapping outside the confines of the coil tend quickly to get out of control, and buckling and tangles often result. This leads to losses in operating time and possible damage to some of the strapping. In addition, occasions have been encountered in the past wherein loose and uncontrolled convolutions of strapping have sprung out of a coil, much in the fashion that might be expected of a clock spring, when slack has developed in that uncontrolled portion of strapping which has just been withdrawn from the coil.

One of the principal objects of the present invention is to solve the foregoing problems by providing, in mechanism for dispensing strapping or the like, relatively simple and very inexpensive apparatus which automatically assumes control of the slack or un tensioned strapping by gripping the same in response to the tendency of the strapping to buckle. Another object of the invention is to provide such apparatus wherein a controlled buckling of the strapping is intentionally permitted to occur to take up any slack that arises in the strapping and wherein the buckling force of the strapping is itself used to generate the gripping force for controlling the strapping. Still another object of the invention is to provide such apparatus wherein the strap gripping force is progressively and automatically increased as the slack absorbing buckling increases, so that the control automatically becomes more forceful and positive as the need therefor increases.

Yet another object of the present invention is to provide simple and inexpensive apparatus of the kind referred to

above, wherein the strap gripping and control mechanism exerts a braking action on the longitudinal movement of the strapping, and wherein this braking action is generated by the buckling forces and automatically is increased as the buckling and need for braking action increases. Still another object is to provide in such apparatus means whereby the gripping and braking mechanism is utilized to control power means for driving the coil from which the strapping or like material is being dispensed. Another object is to provide, in combination with the foregoing apparatus, an improved drive means for the coil and means by which said gripping and braking apparatus may be easily retracted from an obstructing position when a fresh coil is about to be placed in position for dispensing, and wherein the retraction of said apparatus automatically renders inactive the drive means for the coil.

These and other objects and advantages of the present invention will be apparent from the following description of a preferred embodiment thereof, taken with the accompanying drawing, wherein:

FIG. 1 is a top plan view of a strap dispenser constructed in accordance with the invention, a sensor unit being shown both in full lines and in broken lines to represent the movement thereof between different positions, and the discharge path for the strapping being shown by broken lines corresponding to the positions of the sensor unit;

FIG. 2 is an elevational view of the mechanism of FIG. 1, with certain portions of the mechanism being broken away substantially along the line 2—2 in FIG. 1;

FIG. 3 is a perspective view of the apparatus showing the general mode of its operation, with certain details of the apparatus being omitted for simplicity of illustration;

FIG. 4 is a greatly enlarged fragmentary cross-sectional view taken substantially along a horizontal plane passing through a loop provided on the outer end of the sensor unit, with the path of the strap through the loop being shown schematically in solid lines to represent the disposition of the strap with respect to the arms of the loop when the sensor unit is in the solid-line position illustrated in FIG. 1, and with the disposition of the strapping with respect to the loop being shown in broken lines to represent the relative position of the strapping with respect to the loop when the sensor unit is in the broken-line position thereof illustrated in FIG. 1.

As shown in the drawing, the apparatus includes a housing 10 of sheet metal or the like having a bottom wall 11, a front wall 12 which slopes diagonally upwardly from the front edge of the bottom wall 11, and a top wall 13 which may join the upper-edge portion of the front wall 12 in a gradual curve, the casing or housing 10 being provided with opposite end walls 14 and 15. The apparatus also includes a rigid base frame which is comprised, in part, of a pair of frame members 16 and 17, each of which may be fabricated from channel iron or the like of U-shaped cross section. The two frame members 16 and 17 are secured in any suitable manner, as by welding or the like, upon the upper side of the bottom wall 11 of the housing 10, and the two frame members extend rearwardly from the open rear portion of the casing 10 and thereupon converge toward each other, as illustrated in FIG. 1. The converging ends of the frame members 16 and 17 are joined, as by welding or the like, by a further frame member 18 which may comprise a bar bent adjacent its middle. As seen in FIG. 1, the bent middle portion of the bar 18 is joined to the outermost converging ends of the frame members 16 and 17, so that the remaining portions of the bar 18 provide radially-extending base supports. The lower-edge portions of the frame members 16, 17 and 18, as well as

the bottom wall 11 of the housing 10, are adapted to rest directly upon a supporting floor, not shown.

A wheel-like support for the coil of strapping to be unwound and dispensed is pivotally mounted upon the base in any suitable manner above the area of the junction of the frame members 16, 17 and 18 for rotation in a coil-unwinding direction about a vertical axis. In the particular apparatus illustrated, an upstanding shaft 19 is welded or otherwise secured at its lower end to the converging ends of the frame members 16 and 17, in the position best seen in FIGS. 1 and 2. A collar 20 is fixed to this shaft above the frame members 16, 17 and 18, and a hub of any suitable construction is rotatably mounted upon the shaft 19 above the collar 20. In the particular form of the apparatus illustrated in FIG. 2, this hub is comprised of a pair of commercially available casings or housings 21 and 22 containing ball bearings and suitable races, so that the housing 21 and 22 will rotate freely with respect to the shaft 19 and about its axis. If desired, the housings 21 and 22 and the ball-bearing mechanisms contained therein may be such that the bearing assembly within the casing 21 may rotatably rest upon the upper side of the collar 20. The bearing mechanism within the casing 22 may correspond to that employed within the casing 21, and an upper collar 23 may be secured to the shaft 19 above the casing 22 and its bearing mechanism, so that the latter may not be moved axially upwardly along the shaft 19.

In the form of the apparatus illustrated in FIG. 2, the bearing casings 21 and 22 are respectively provided with outwardly-extending flanges 24 and 25, which are fixed upon the casings. A plurality of bolts 26, provided with suitable washers if desired, are passed through appropriate openings in the flanges 24 and 25, and a pair of annular clamping plates 27 and 28 are mounted on these bolts between the flanges 24 and 25.

A plurality of radially-extending supporting arms 29, of inverted U-shaped cross section, are mounted at their inner ends between the clamp plates 27 and 28. For this purpose, the inner ends of the arms 29 are provided with stubs 30 which are disposed between the two plates 27 and 28. A bolt 31 is passed downwardly through the upper wall of each supporting arm 29 and through the two clamp plates 27 and 28, it being understood that, when the nuts provided on the bolts are tightened, the two clamp plates are respectively drawn tightly against the upper and lower edges of the stub portion 30 of each arm 29, thereby to retain each arm in a rigid radially-directed position with respect to the clamp plates 27 and 28 and with respect to the flanges 24 and 25 provided on the casings 21 and 22 of the hub assembly. The outer-end portions of the supporting arms 29 are undercut, and these undercut portions have secured thereto a circular rim 32 of inverted L-shaped cross section, the rim 32 thus being provided with a horizontally-projecting annular flange 32a and a downwardly extending flange 32b, both of which flanges may be secured, as by welding or the like, within the undercut portions at the outer ends of the respective supporting arms 29.

The under surface of the flange 32a of the rim 32 serves as a frictional drive surface for the coil-supporting wheel assembly, as will be later explained herein.

Upstanding stub arms 33, which may also be of U-shaped cross section, if desired, are welded or otherwise secured to the upper surfaces of the respective support arms 29 adjacent their outer ends, as best seen in FIGS. 1 and 2. The coil of strapping 34 to be unwound is represented by broken lines in FIG. 2, and it will be observed that this coil simply rests on its side upon the upper surfaces of the respective supporting arms 29, the upstanding stub arms 33 serving to insure that the coil is not displaced from its position on the supporting arms 29.

A generally cylindrical bell-like cap 35, open at its bottom end, rests in inverted position upon the upper surfaces of the radially extending support arms 29, so as

to cover the hub portions of the coil-supporting wheel assembly and the clamping bolts 31 which secure the inner ends of the arms 29 between the clamp plates 27 and 28. This bell-like cap 35 is closed at its upper end by a wall 36, as best seen in FIG. 2, and the bell-like cap is secured in position by a screw 37 which extends downwardly through the center of the wall 36 and is suitably threaded into the upper end of the shaft 19.

Within the housing 10 there is provided an electric drive motor 40 which serves to rotate the coil-supporting wheel assembly in the coil unwinding direction represented by the arrow 41 in FIGS. 1 and 3. This electric motor has secured thereto a motor-supporting yoke 42. The upstanding legs 42a of the yoke 42 are provided on opposite sides of the motor with coaxial pinions 43 which are rotatably journaled in the upstanding legs of another yoke 44 which may be secured in any suitable fashion, such as by welding or the like, upon the upper surface of the wall 11, within the housing 10. It will be observed that the yoke 42 and the pinions 42a are disposed adjacent the drive end of the motor 40, so that the motor will pivot about the axes of the pinions 43, with the weight of the body of the motor tending always to urge the motor to be pivoted in the direction of the arrow 45 in FIG. 2. The drive shaft of the motor is provided with a drive wheel 46 of rubber or the like which is disposed directly beneath the flange 32a of the rim 32 and in driving contact therewith. Thus, the weight of the motor 40 and its tendency constantly to be pivoted in the direction of the arrow 45 causes the periphery of the drive wheel 46 to bear constantly upon the drive surface on the underside of the flange 32a of the rim 32. It will also be observed that the pivotal mounting of the motor 40 will cause the drive wheel 46 to be continuously and in uniform driving engagement with the flange 32a, despite the fact that the undersurface of the flange may have irregularities therein or may not lie precisely in a plane that is horizontal or is normal to the axis of the shaft 19. Thus, the pivotal mounting of the motor and the drive arrangement just described allows for wide constructional tolerances and provides constant drive force despite any irregularities that may exist.

Electric energy for the motor 40 may be provided by a cable 50 connected to a power source, not shown, and the cable, if desired, may be of the disconnect type which may be plugged into any suitable electric receptacle 50a carried by the wall 14 of the housing 10. The electric leads from the cable are shown schematically in FIG. 1 and extend through the wall 14 of the housing 10. One of the leads 51 may extend directly to one of the terminals of the motor 40. The other lead 52 extends to one side of a normally open, plunger type commercially available micro switch 53 which may be mounted, as by screws 54, upon the underside of the upper wall 13 of the housing 10. Another electrical lead 52a extends from the other side of the normally open switch 53 to the other terminal of the motor 40, so that the motor 40 will operate and will drive the coil-supporting wheel assembly only when the switch 53 is closed. In actual practice, a manually operated "on-off" switch is employed in the lead 52 in electrical series with the switch 53, but for simplicity of illustration this manual switch has not been shown in the drawing.

A bracket 60, having a pair of upstanding ears 61 at its opposite ends, is secured, as by welding or the like, upon the upper surface of the upper wall 13 of the housing 10. A second bracket assembly 62 having at its opposite ends depending ears 63 which are pivotally mounted, as by loose rivets or the like, upon the upstanding ears 61 of the bracket 60. The bracket assembly 62 thus provides an upper wall 64 which extends between the ears 63, and a lower wall 65 also extends between the ears 63, the lower wall 65 being secured in any suitable way between the ears 63 in fixed, spaced position with respect to the wall 64 and directly therebeneath. A base block 66 of a sensor unit 67 is pivotally mounted between the upper

and lower walls 64 and 65 of the bracket assembly 62 by means of a vertically disposed pin 68 which is fixed to the block 66 and the opposite ends of which are journaled in the walls 64 and 65 for free rotation therein. The lower end of the pin 68, when the bracket 62 is in its normal, full-line position shown in FIG. 2, extends downwardly through a rearwardly opening slot provided in the upper wall 13 of the housing 10, the lowermost end of the pin 68 having a cam block 69 fixed thereon. One end of this cam block 69 is provided with a cam surface 70 which is adapted to engage a roller 71 provided on the outer end of a leaf-type actuator 72, of an ordinary commercial type, fixed upon the switch 53 in a well-known manner, it being understood that, when the cam block 69 is rotated to engage the roller 71 and deflect the actuator leaf 72, the switch 53 will be closed to cause the motor 40 to be energized and rotatably drive the coil-supporting wheel assembly previously described.

The sensor unit 67 is preferably of light weight but sturdy wire or rod construction. An arm 67a of the sensor unit is fixed at its inner end in the pivotally mounted base block 66, and the arm 67a extends outwardly as shown in FIGS. 1, 2 and 3, the outermost end of the arm 67a being formed to provide a loop comprising a pair of vertically oriented, parallel, spaced apart rod lengths 67b and 67c joined at their lower ends by a rod length 67d. It will also be observed in FIG. 2 that the upper portion of the loop provided by the rod lengths 67b and 67c and the rod length 67d is closed by another rod length 67e. In the preferred construction, the arm 67a and the elements of the loop are of the very inexpensive unitary construction illustrated in the drawing.

Due to the fact that the depending ears 63 of the bracket assembly 62 are pivotally mounted upon the upstanding ears 61 of the bracket 60, it will be appreciated that the entire bracket assembly 62, with the base block 66 and the cam block 69, as well as the entire sensor unit 67, may be pivoted upwardly in the direction of the arrow 70 to the broken line position illustrated in FIG. 2. Thus, the sensor unit 67 may be elevated and retracted from the area above the coil-supporting wheel assembly when a fresh coil 34 of strapping is being placed upon the coil-supporting wheel assembly. This will avoid any damage to the sensor unit 67 during the loading of the apparatus with a fresh coil of strapping, and it will be appreciated that the retraction or elevation of the bracket assembly 62 from its full-line position in FIG. 2 to its broken-line position, will carry the cam block 69 to a position remote from the switch actuator 72, thereby avoiding any inadvertent energization of the drive motor 40 during the loading of the apparatus.

In the unwinding of the strapping from a coil with the use of the apparatus of the present invention, the strapping is normally unwound from the inside of the coil 34, as best illustrated in FIG. 3. The strapping, being unwound from the coil, passes through a curved discharge path leading toward a discharge guide tube 80 which is secured by a pin 31 or the like upon the underside of the upper wall 64 of the bracket assembly 62. The strapping passes through the guide tube 80, and this guide, if desired, may be in the form of a helical spring, as illustrated in the drawings. It will be observed that the vertical walls of the bell-like cap 35 will serve, in part, to guide and retain the loose convolutions of the strapping within the coil, and it will also be observed that the discharge path followed by the strapping, as it moves from the central area of the coil 34, is curved in the direction of curvature of the strapping within the coil. It will also be observed that the strapping passes through the loop provided on the outer end of the sensor arm 67a.

In loading the apparatus with a fresh coil of strapping, the entire bracket assembly 62 and the sensor unit 67, together with their related parts, are pivoted upwardly to the broken-line position illustrated in FIG. 2, as previously mentioned. The fresh coil of strapping is then laid

on its side on the upper surfaces of the arms 29 in the position indicated by the solid lines in FIG. 3 and by the broken lines in FIG. 2. The bracket assembly 62 and the sensor unit 67 are then lowered to the full line position shown in FIG. 2. During the loading, it is, of course desirable that the manually operated switch, previously referred to but not shown in the drawing, be maintained in the "off" position so that the motor will not be energized inadvertently when the sensor unit 67 is lowered to its full line position.

With the elements in the condition just described, a length of the free end of the strapping is uncoiled from the inside of the coil 34, and this free end portion of the strapping is manually threaded through the loop provided on the outer end of the sensor unit 67, care being taken to insure that the strapping is passed on the inside of the rod length 67c and on the outside of the rod length 67b, as illustrated in FIG. 4. The free end of the strapping is then threaded through the exit guide tube 80, thus providing a length of the strapping outside the confines of the present apparatus, which length may be gripped manually and later pulled or may be fed into a strapping machine or other device which utilizes or consumes strapping. As a last step in the loading, sufficient strapping should be withdrawn from the coil 34 to insure that the strapping lies substantially along the discharge path 34b, as shown in FIG. 1, so that the motor 40 will not be prematurely energized. Finally, if a manually operated switch is employed, as previously described, it should be moved to the "on" position.

In the preferred form of the apparatus, a headed screw 66a (shown only in FIG. 1) is threaded into one side of the pivoted base 65 of the sensor unit 67 in order adjustably to limit the outermost pivotal limit of the sensor unit, the head of the screw 66a being adapted to bump the inside surface of the ear 63 of the bracket assembly 62.

It will be observed that, after the strapping has been loaded in the manner just described, a pull on the outermost end of the strapping, whether the pull is applied manually or by another machine, will cause the sensor unit 67 to pivot from the full line position shown in FIG. 1 toward and into the broken line position of the sensor unit illustrated in FIG. 1. The pivotation of the sensor unit toward or into the broken line position seen in FIG. 1 will cause the cam surface 70 on the cam block 69 to engage the wheel 71 of the switch actuator 72, thereby depressing the switch actuator and electrically closing the switch 53. This will energize the motor 40 and cause the drive wheel 46 thereon to drive the coil-supporting wheel assembly by means of the frictional contact of the wheel 46 upon the under surface of the flange 32a, of the rim 32.

This driven rotation of the coil-supporting wheel assembly will rotate the coil 34 in the coil unwinding direction and thus will feed strapping from the coil through the loop on the outer end of the sensor unit and through the exit guide tube 80. During this driving and dispensing action of the mechanism, and during such time as the rate of withdrawal of the strapping away from the present machine remains substantially as great as the rate at which the strapping is fed off of the coil, the strapping will follow a discharge path to the exit guide tube 80 generally along the path indicated by the numeral 34a in FIG. 1. This discharge path, in the immediate area of the loop at the free end of the sensor unit 67, is schematically illustrated by the broken line representation of the strapping in FIG. 4, it being observed that the longitudinally concave side of the strapping passes across the rod length 67b, but is, at this time, normally out of contact with the other rod length 67c which is always spaced from the rod length 67b a fixed distance and is disposed opposite the convex side of the strapping and displaced from the rod length 67b in the direction opposite the direction of the longitudinal movement of the strapping. So long as the withdrawal of strapping from the ap-

paratus proceeds at a rate that is not substantially less than the rate at which the strapping is unwound from the coil by the driving action of the motor 40, the strapping, within the area of the present apparatus, will continue to follow substantially the discharge path designated in the drawings by the numeral 34a. However, if the withdrawal of the strapping should cease, or if the rate at which the strapping is withdrawn falls substantially below the rate at which the strapping is unwound from the coil by virtue of the driving action of the motor 40, the strapping in the discharge path within the apparatus and ahead of the guide tube 80 will start to buckle or bulge outwardly toward the broken line strapping discharge path designated by the numeral 34b in FIG. 1, this same discharge path 34b being schematically illustrated by solid line representation of the strapping in FIG. 4. As the accumulation of excess strapping in the area of the discharge path within the machine grows, the continuing increase in the outward buckling of the strapping will likewise grow and will, consequently, begin to pivot the sensor unit 67 from its broken line position in FIG. 1 toward its full line position. At the same time, as the buckling condition grows, the convex side of the strapping in the area of the discharge path will approach closer and closer to the rod length 67c of the loop at the outer end of the sensor unit. As the sensor unit in its pivotal movement, moves toward the full line position thereof shown in FIG. 1, the cam surface 70 on the cam block 69 will become disengaged from the roller 71 on the switch actuator 72, and will interrupt the electrical energization of the drive motor 40, thereby to interrupt the application of driving power to the coil-supporting wheel assembly. Furthermore, as the buckling grows, the convex or outer side of the strapping in the area of the discharge path will come into forceful contact with the rod length 67c of the loop at the outer end of the sensor unit 67. Subsequent to the termination of the application of power to the coil-supporting wheel assembly, the inertia of the wheel assembly and the coil of strapping supported thereon will cause the wheel assembly and the coil to coast momentarily before they come to a complete stop. This coasting will tend to cause the outward force of the outwardly buckled strapping in the area of the discharge path to be increased, thereby further increasing the force applied by the concave or inner side of the strapping upon the rod length 67b of the loop at the outer end of the sensor unit 67, and simultaneously increasing the force applied by the convex or outer side of the strapping to the rod length 67c of the loop. These forces applied by the buckled strapping upon the rod lengths 67b and 67c are schematically represented by the arrows 100 and 101 in FIG. 4, and it will be understood that they are generated by the force of the buckling strap itself. Thus, it will be seen that the bulged strapping tends frictionally to bind forcefully between the rod lengths 67b and 67c, so that these rod lengths exert both a braking force upon the continued movement of the strapping past the rod lengths 67b and 67c, and also a strap gripping force. The braking action just referred to stops the further feeding of strapping from the coil 34 into the discharge path of the strapping, thereby stopping the buckling, and the gripping action afforded by the rod lengths 67b and 67c causes full control to be captured over the strapping in the discharge path. This control over the strapping is augmented by the fact that the top and bottom of the loop at the outer end of the sensor unit 67 are closed by the rod lengths 67d and 67e so that the strapping cannot, under any circumstance, slip upwardly or downwardly out of the grip of the rod lengths 67b and 67c, which are parallel and are also substantially parallel to the axis of the shaft 19.

The result of the gripping and braking action exerted by the rod lengths 67b and 67c of the loop at the outer end of the sensor unit 67 is that the prior problem of

loss of control of the strapping, with the occasional springing of convolutions of strapping from the coil 34, is entirely overcome and avoided. The strapping is thus maintained in close and positive control, with the strapping being firmly held in the discharge path and in the position represented in the drawings by the numeral 34b, until withdrawal of further strapping from the present apparatus is resumed. Upon the resumption of such withdrawal, the tug or pull on the outer end of the strapping first reduces the buckle of the strapping in the discharge path 34b between the exit guide tube 80 and the loop at the outer end of the sensor unit 67, and further withdrawal of strapping causes the sensor unit to begin to pivot from its full line position illustrated in FIG. 1 toward its broken line position. This pivotation of the sensor unit gradually causes the grip on the strapping to be released and again causes the cam surface 70 on the cam block 69 to engage the wheel 71 of the switch actuator 72, thereby again closing the switch 53 and resuming the driving action exerted by the motor 40 upon the coil-supporting wheel assembly. Thus, power-driven dispensing action is resumed after having been previously interrupted, without the operator having touched the machine or having experienced any loss of control or tangling or damage to the strapping.

In summary, it is to be noted that the inside or longitudinally concave side of the strapping is in contact with the rod length 67b of the loop at the outer end of the sensor unit 67 when the sensor unit is in either of the positions thereof shown in the drawing, and that the outer or convex side of the strapping engages and begins making ever increasingly forceful contact with the rod length 67c as the strapping begins to buckle outwardly from the path 34a toward the path designated by the numeral 34b. These conditions are illustrated schematically in FIG. 4 and it will there be seen that the two rod lengths 67b and 67c lie in a plane which intersects the general plane of the strapping therebetween at an acute angle, that angle decreasing as the buckling of the strapping increases and as the sensor unit 67 is pivoted from its broken line position toward its full line position (as seen in FIG. 1), and with the angle increasing as the buckling decreases and the sensor unit is pivoted from its full line position (FIG. 1) toward its broken line position. Thus, the rod lengths 67b and 67c automatically assume control of the slack or untensioned strapping, by virtue of their gripping and braking action, at the very time control is needed and in response to the tendency of the strapping to buckle, and the gripping and braking action, which is generated by the buckling of the strapping itself, is progressively and automatically increased as the buckling increases, thereby exerting greater control when greater control is needed.

Although only one specific embodiment of the present invention has been shown in the drawing and described above for purposes of illustration, it will be understood by those skilled in the art that various changes and modifications may be made therein, and it will also be understood that the invention may be employed for dispensing wire and materials other than strapping. Accordingly, when the words "strap" or "strapping" are used in the appended claims, it is intended to mean both strapping and wire and like materials, and it is intended to cover in the appended claims all modifications as fall within the true spirit and scope of the invention.

We claim:

1. In mechanism for dispensing strapping and the like from a coil thereof, the combination comprising, means for supporting the coil for rotation about an axis, means including motor means for driving said supporting means in a coil-unwinding direction about said axis and for feeding the strapping from the coil along a curved discharge path wherein the strapping is curved in the same direction as the curvature of the strapping in the coil and wherein one side of the strapping is concave in the longitudinal direction thereof and the other side of said strapping is

convex, a movable sensor unit, a first strap engaging member on said sensor unit adapted to contact said concave side of said strapping in the area of said discharge path, a second strap engaging member on said sensor unit adapted to contact said convex side of said strapping, said second strap engaging member being disposed in an adjacent predetermined spaced-apart position with respect to said first strap engaging member and being displaced from said first strap engaging member in the direction opposite the direction of movement of said strapping through said discharge path, said strapping tending to bulge outwardly with respect to said discharge path and to move said strap engaging members and said sensor unit therewith when the rate of removal of said strapping along said discharge path becomes substantially less than the rate at which the strapping is unwound from the coil, the strapping in the bulged portion thereof tending to bind between said strap engaging members, whereby said strap engaging members serve to grip the bulged strapping therebetween and prevent loss of control thereof, and means responsive to the movement of said sensor unit for controlling said motor means.

2. In mechanism for dispensing strapping and the like from a coil thereof, the combination comprising, means for supporting the coil for rotation about an axis, a strap guide, means including motor means for driving said supporting means in a coil-unwinding direction about said axis and for feeding the strapping along a curved discharge path from the coil to said guide, one side of the strapping in said curved path being longitudinally concave and the other side thereof being convex, a movable sensor unit, a first strap engaging member on said sensor unit adapted to contact said concave side of said strapping in the area of said discharge path, a second strap engaging member on said sensor unit adapted to contact said convex side of said strapping, said second strap engaging member being disposed in an adjacent predetermined spaced-apart position with respect to said first strap engaging member and being displaced from said first strap engaging member in the direction opposite the direction of movement of said strapping through said discharge path, said strapping tending to bulge outwardly with respect to said discharge path and to move said strap engaging members and said sensor unit therewith when the rate of removal of said strapping along said discharge path becomes substantially less than the rate at which the strapping is unwound from the coil, the strapping in the bulged portion thereof tending to bind between said strap engaging members, whereby said strap engaging members serve to grip the bulged strapping therebetween and prevent loss of control thereof, and means responsive to the movement of said sensor unit for controlling said motor means.

3. The combination set forth in claim 2, wherein said sensor unit comprises a pivoted arm carrying said strap engaging members.

4. The combination set forth in claim 2, wherein said sensor unit comprises an arm pivotally mounted adjacent said guide and wherein said strap engaging members are on a free end portion of said arm.

5. The combination set forth in claim 2, wherein said sensor unit comprises a light weight arm pivotally mounted adjacent said guide, and where said strap engaging members comprise the opposite sides of a substantially closed loop on a free end of said arm.

6. The combination set forth in claim 5, wherein said strap engaging members are provided with friction surfaces for gripping said strapping and for braking the longitudinal movement of said strapping.

7. In mechanism for dispensing strapping and the like from a coil thereof, the combination comprising, a ro-

tatable wheel assembly for supporting the coil for rotation about a substantially vertical axis, a strap guide adjacent said wheel assembly, means including an electric motor for driving said wheel assembly in a coil-unwinding direction and for feeding strapping along a curved discharge path from said coil to and through said guide, one side of the strapping in said curved path being longitudinally concave and the other side thereof being convex, a sensor arm pivotally mounted adjacent said guide and projecting in a direction generally in alignment with and adjacent said discharge path, a first strap engaging member on said sensor arm adapted to contact said concave side of said strapping in said discharge path, a second strap engaging member on said sensor arm adapted to contact said convex side of said strapping, said second strap engaging member being disposed in an adjacent predetermined spaced-apart position with respect to said first strap engaging member and being displaced from said first strap engaging member in the direction opposite the direction of movement of said strapping from said coil to said guide, said strapping tending to bulge outwardly with respect to said discharge path and thereby to move said strap engaging members and pivot said sensor arm when the rate of removal of said strapping through said guide becomes substantially less than the rate at which the strapping is unwound from the coil, the strapping in the bulged portion thereof tending to bind between said strap engaging members, whereby said strap engaging members grip the bulged strapping therebetween and prevent loss of control thereof, a switch for controlling the energization of said motor, and means connected to said sensor arm for actuating said switch in response to pivotal movement of said arm.

8. The combination set forth in claim 7, wherein said sensor arm is also pivotal upwardly away from the area of said discharge path and wherein said switch actuating means is carried to a position remote from said switch by the upward pivotal motion of said arm, thereby to remove said sensor arm from said area of said discharge path and at the same time avoid actuation of said switch.

9. The combination set forth in claim 7, wherein said rotatable wheel assembly includes a rim, said electric motor is provided with a friction wheel drivingly engaging an under surface of said rim, and said motor is pivotally mounted adjacent said friction wheel, whereby the weight of said motor causes said friction wheel constantly to bear upon said under surface of said rim despite irregularities that may exist in said rim.

10. In mechanism for dispensing strapping and the like from a coil thereof, means for supporting the coil for rotation about an axis, means including motor means for driving said supporting means in a coil-unwinding direction about said axis and for feeding the strapping along a curved discharge path, a movable sensor unit, means on said sensor unit in substantially constant contact with said strapping in said discharge path and gripping said strapping when said sensor unit is moved responsive to bulging of said strapping with respect to said discharge path, and means responsive to the movement of said sensor unit for controlling said motor means.
